UNITED STATES PATENT OFFICE.

GEORGE B. CLARK, OF BETHESDA, OHIO.

CUTTER-BAR.

SPECIFICATION forming part of Letters Patent No. 449,521, dated March 31, 1891.

Application filed October 25, 1890. Serial No. 369,334. (No model.)

To all whom it may concern:

Be it known that I, GEORGE B. CLARK, a citizen of the United States, and a resident of Bethesda, in the county of Belmont and State of Ohio, have invented certain new and useful Improvements in Means for Fastening and Tightening the Knives of Harvester Cutting Apparatus; and I do declare the following to be a full, clear, and exact description of the invention, such as will enable others skilled in the art to which it appertains to make and use the same, reference being had to the accompanying drawings, and to the letters of reference marked thereon, which form a part of this specification.

Figure 1 of the drawings is a top plan view of the invention, also showing the locking-bar raised in dotted lines. Fig. 2 is a plan view with locking-bar removed, and Fig. 3 is a horizontal section.

The invention relates to improvements in means for fastening and tightening the knives in the cutting apparatus of harvesting and mowing machines; and it consists in the novel construction and combination of parts hereinafter fully described.

In the accompanying drawings, A represents the knife-bar, which is provided along its upper surface with a series of headed studs or pins *a*, projecting upwardly a short distance therefrom. These pins or studs *a* are so arranged that they will register with the slots or perforations *b* in the knives B when the said parts are brought together. The slots or perforations *b*, two preferably in each knife, are located near the upper edge of the knife and extend in a direction parallel to the knife-bar. At one end these slots *b* are formed with an enlarged portion *b'*, adapted to receive the heads of the pins or studs *a*. The knives are placed on the knife-bar, the enlarged portions of the slots *b* receiving the headed pins or studs. The knives are then moved forwardly with reference to the knife-bar, so as to bring the narrow portion of the slots in engagement with the shanks of the pins or studs, the heads of the pins preventing vertical movement.

D represents the locking plate or bar, which consists of a metal plate or piece somewhat greater in length than the space occupied by the knives on the knife-bar and of suitable width and thickness. At one end this piece or plate D is provided with a slot or perfora-

tion *d*, similar to the slots *b* in the knives, 55 except that the enlarged portion *d'* thereof is at the opposite end of the slot. Near the opposite end a perforation *e* is provided, which is adapted to receive a set-screw or locking-pin, as will be hereinafter described. Intermediate of these end perforations the plate or bar D is provided with a series of slots *f*, running in from the forward edge or margin thereof, as shown. These slots are the same distance apart and correspond in number to 65 the headed pins or studs *a*, with which they are adapted to register when the parts are brought into locking position and which they receive. The outer end pin or stud *a* is inserted in the enlarged portion *d'* of the slot *d* 70 of the bar or plate D and the said bar or plate moved endwise, so as to bring the narrow portion of the said slot in engagement with the shank of the pin. Said bar or plate is then brought forward, the pin *a* serving 75 as a pivot, the perpendicular slots engaging the shanks of the pins or studs *b* between the surface of the knives and the heads of the pins. As the bar is thus brought down to its lowest position, it will be seen that it will 80 draw the knives firmly and securely to their place. The bar D is then secured in such position by the set-screw or locking-pin *g*, which enters the perforation *e* of said bar and engages the knife-bar. In this manner 85 the knives will be securely held.

Having thus described the invention, what I claim, and I desire to secure by Letters Patent, is—

The fastening and tightening device for 90 mower and harvester knives, comprising the longitudinal bar or plate D, adjustably pivoted at one end to the knife-bar and provided at its intermediate portion with the transverse marginal slots *f*, in combination with 95 the knife-bar having the headed pins or studs which engage and lock the knives in position, said studs or pins registering with and adapted to enter said perforations or slots, and means for locking the parts in such adjustment, substantially as specified.

In testimony whereof I affix my signature in presence of two witnesses.

GEORGE B. CLARK.
